Primary Examiner — Selina Sikder(74) *Attorney, Agent, or Firm* — Keating & Bennett, LLP(57) **CLAIM**

The ornamental design for an automotive switch, as shown and described.

DESCRIPTION

FIG. 1 is a front view of an automotive switch showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a top perspective view thereof;

FIG. 8 is a front view of the knob thereof shown without the base;

FIG. 9 is a rear view thereof;

FIG. 10 is a right side view thereof;

FIG. 11 is a left side view thereof;

FIG. 12 is a top plan view thereof;

FIG. 13 is a bottom plan view thereof; and,

FIG. 14 is a top perspective view thereof.

The dash-dash broken lines in the drawing views are included to show portions of the automotive switch that form no part of the claimed design. The dash-dot broken lines in the drawing views are included to show claim boundaries that form no part of the claimed design.
